UNITED STATES PATENT OFFICE.

MAURICE GRAHAM, OF LEEDS, ENGLAND.

HOT-COKE CONVEYER.

SPECIFICATION forming part of Letters Patent No. 732,545, dated June 30, 1903.

Application filed March 10, 1903. Serial No. 147,185. (No model.)

To all whom it may concern:

Be it known that I, MAURICE GRAHAM, a subject of the King of Great Britain and Ireland, residing in Leeds, county of York, England, have invented certain new and useful Improvements in Hot-Coke Conveyers, of which the following is a specification.

The object of this invention is to provide in a conveyer for the hot coke discharged from the retorts of gas-furnaces means for preventing the escape of steam and objectionable gases from the coke into the adjacent space within the gas-house.

For this purpose the invention consists in the combination, with a retort-setting or plurality of settings, of a conveying mechanism arranged at the discharge end of said setting for receiving the coke therefrom, a housing inclosing said conveyer and adapted to permit the passage of the conveying device therethrough, an exhaust pipe or pipes connected with said housing opposite said retort setting or settings, respectively, and a fan or fans connected with said exhaust pipe or pipes for drawing off the noxious vapors and steam arising from the coke within said housing.

The invention consists, further, in certain details of construction and combinations of parts, which will be fully described herein-after and finally claimed.

In the accompanying drawings, Figure 1 is an elevation showing the rear or discharging ends of a plurality of retort-settings with my improved conveyer arranged in position for conducting off the coke discharged therefrom. Fig. 2 is a plan view of a portion of the conveyer-chain. Fig. 3 is a vertical transverse section, on a larger scale, on line 3 3, Fig. 1. Fig. 4 is a plan view of Fig. 1, showing also the gas-house wall and retort-work in cross-section. Fig. 5 is a vertical longitudinal section, on a larger scale, on line 5 5, Fig. 4. Fig. 6 is a side view of a portion of the conveying-chain and one of its supporting-drums; and Fig. 7 is a vertical transverse section on line 7 7, Fig. 6.

Similar letters of reference indicate corresponding parts.

Referring to the drawings, A' A² A³ A⁴ A⁵ A⁶ indicate retort-settings of the ordinary or any preferred construction.

a indicates the individual retorts.

The conveying device proper consists of an endless chain B, formed of individual links, each link having the shape of a grid b and pivotally connected with the next by means of a pivot-pin b', as shown. At the ends of the pivot-pin b' are mounted rollers b², which engage guide-rails b³, suitably supported by bracket-irons b⁴, whereby the conveyer device proper is supported and guided so as to have longitudinal movement, passing in its travel the several retort-settings. The bracket-irons b⁴ are connected with and supported by an exterior housing D, provided with a bottom d, an inner side wall d', an outer side wall d'', said side walls extending in upward direction, a top e, two channel-irons e' e'', and a hinged cover or covers e³.

E indicates transverse I-beams, suitably supported at their ends, into which the channel-irons e' are set at their ends, as indicated in Fig. 1, whereby the entire conveyer is supported. The hinged doors are preferably pivoted one at each side adjacent the upper 75 surface of the I-beams, as shown.

In order to prevent the overflow of the coke from the conveying device proper into the housing, shield-plates f f', respectively, are arranged one at each side of the conveying-chain, depending toward the same from the cover or top plates of the housing, as shown in Fig. 2. Below the conveying-chain is arranged a trough formed by two upright side walls g g'. The bracket or channel-irons b⁴ serve to retain the trough-plates in upright position and tighten the connection of the same with the bottom plate d of the housing, so as to render the trough water-tight.

Spray-pipes h h' are arranged at the upper 90 part of the conveyer within the same in such position as to direct a spray of water upon the coke being conveyed.

Connected with the outer wall of the conveyer-housing opposite each retort-setting is an exhaust-pipe m. The pipes m may extend independently to any suitable point outside the wall m' of the gas-house or may be all connected with one main or trunk exhaust-pipe m², which extends to the outside of the 100 gas-house or to any suitable place of discharge. In case the exhaust-pipes m extend directly to the point of discharge each is provided at some point in its length with a suitable fan

or suction device m^3 . In case all the individual or branch exhaust-pipes m are connected to one main exhaust-pipe the latter is provided with a fan m^4 . For the sake of 5 illustration in Fig. 4 one of the exhaust-pipes is run directly to the exterior of the gas-house, while the remainder are connected to a main exhaust-pipe.

The conveyer-chain is supported at each 10 end at a point beyond the conveyer by means of guide rollers or drums n n' . The return-passage of the chain is made outside the conveyer-housing over similar drums n^2 n^3 . The conveyer-housing is provided at its entrance 15 end with an inwardly-folding flap-door p , adapted to swing in a vertical plane and permit the entrance of the conveyer-chain in an empty condition. The outgoing end of the conveyer-housing is provided with a similarly-pivoted outwardly-opening flap-door p' , adapted to permit the passage in outward direction of the conveyer-chain with the coke thereon. For receiving the coke as the chain 20 passes over the guide-wheel n' , a chute r is arranged, adapted to discharge into any desired receptacle. For keeping clear of obstruction 25 the trough below the conveyer-chain in the housing the chain is provided at suitable intervals with depending push-plates s of approximately the same shape and area as the 30 transverse section of the trough. These plates during the passage of the conveyer pass along in the trough and scrape any obstruction or accumulation of dust or coke therein into 35 suitable discharge-pipes t , connected with the bottom d of the housing and extending to the ground below or to any suitable point of discharge.

The operation of the conveyer will be 40 apparent from the foregoing. Coke from the retorts a is transferred in a highly-heated condition by means of a chute or any other suitable means from the retorts into the passage or doorway between the channel-irons, 45 the doors having been previously opened. The coke falls upon the conveyer-chain, which has a slow forward movement. The discharge having been completed, the doors are immediately closed. The spray from the 50 quench-pipes falling upon the highly-heated coke during and subsequent to the discharge is converted into steam. Noxious gases of various kinds also arise from the coke. The fan or fans connected with the exhaust-pipes 55 are in motion and create a suction through the system of exhaust-pipes, thereby drawing off the steam and noxious vapors. Exterior air to supply the place of the air and vapors drawn off may enter the housing at the ends 60 of the same or through spaces between the doors at the top of the conveyer. The principal amount of air will, however, enter at the doors when the latter are opened during the entrance of the coke. The escape of 65 steam and noxious vapors during this necessary opening of the doors is overcome by this invention. This useful effect is produced by

the powerful draft of the fans, which thereby draw down into the housing and suck away to a proper point of discharge all those noxious vapors and the immense quantity of steam which would otherwise rise and escape into the gas-house when the doors were open for the discharge of coke from the retorts onto the conveyer.

Motion is imparted to the shaft of one of the drums—as, for example, the drum n —by means of any suitable mechanism, such as sprocket-and-chain transmission t' , from any suitable source of power, (not shown in the drawings,) said shaft u being under such conditions the driving-shaft for the conveyer and the drum n the driving-wheel. The fans may be operated by power obtained from any suitable source. All accumulations of dirt, 85 dust, and water in the trough are swept out of the same by the push-plates into the waste-pipes during the movement of the conveyer-chain.

It is obvious that the exhaust-pipes may 90 be connected with the housing at any suitable point of the latter—that is to say, either at the outer side wall, (as shown,) at the inner side wall, at the bottom, or at the top. They may be connected one opposite each retort-setting, or a plurality opposite each setting, or they may be connected opposite alternate settings, as may prove most advantageous in the particular case, without departing from the spirit of the invention.

Having thus described my invention, I claim as new and desire to secure by Letters Patent—

1. A hot-coke conveyer, consisting of a conveying device adapted to receive and carry heated coke, a housing inclosing said conveying device and adapted to permit the passage of the same therethrough, an exhaust-pipe connected with said housing, and a suction device connected with said exhaust-pipe, substantially as set forth.

2. A hot-coke conveyer, consisting of a conveying device adapted to receive and carry heated coke, a housing inclosing said conveying device and adapted to permit the passage of the same therethrough, a plurality of exhaust-pipes connected with said housing at intervals in the length of the same, and a suction device for each exhaust-pipe, substantially as set forth.

3. A hot-coke conveyer, consisting of a conveying device adapted to receive and carry heated coke, a housing inclosing said conveying device and adapted to permit the passage of the same therethrough, a plurality of exhaust-pipes connected with said housing at intervals in the length of the same, a main or trunk exhaust-pipe connected with said exhaust-pipes, and a suction device connected with said trunk exhaust-pipe, substantially as set forth.

4. A hot-coke conveyer, consisting of a conveying device adapted to receive and carry heated coke, a housing inclosing said convey-

ing device and adapted to permit the passage of the same therethrough, a doorway for permitting the entrance of hot coke into said housing and onto the conveyer, doors for closing said doorway, an exhaust-pipe connected with said housing, and a suction device connected with said exhaust-pipe, said exhaust-pipe and suction device being of sufficient capacity to withdraw from said housing the vapors rising from coke supplied thereto and thereby prevent the rising of said vapors through the doorway, substantially as set forth.

5. The combination, with a retort-setting, of a hot-coke conveyer, consisting of a conveying device adapted to receive and carry heated coke, a housing inclosing said conveying device and adapted to permit the passage of the same therethrough, a doorway for permitting the entrance of the hot coke into said housing and upon the conveying device opposite said setting, doors for closing said doorway, an exhaust-pipe connected with said housing opposite said setting, and a suction 25 device connected with said exhaust-pipe, substantially as set forth.

6. The combination, with a plurality of retort-settings, of a hot-coke conveyer, consisting of a conveying device arranged at the discharge ends of said settings and adapted to re-

ceive and carry heated coke, a housing inclosing said conveying device and adapted to permit the passage of the same therethrough, exhaust-pipes connected with said housing, one opposite each of said settings, and a suction 35 device connected with each exhaust-pipe, substantially as set forth.

7. The combination, with a plurality of retort-settings, of a hot-coke conveyer, consisting of a conveying device arranged at the discharge ends of said settings and adapted to receive and carry heated coke, a housing inclosing said conveying device and adapted to permit the passage of the same therethrough, a doorway opposite each setting for permitting 45 the entrance of the heated coke into said housing and upon said conveying device, doors for closing each doorway, exhaust-pipes connected with said housing opposite each setting, a trunk exhaust-pipe connected with 50 said exhaust-pipes, and a suction device connected with said trunk exhaust-pipe, substantially as set forth.

In testimony that I claim the foregoing as my invention I have signed my name in presence of two subscribing witnesses.

MAURICE GRAHAM.
